DISPENSER FOR PAPER TOWELS OR THE LIKE

Victor Shanok and Jesse P. Shanok, both of 863 65th St., Brooklyn 20, N.Y.

Filed May 31, 1962, Ser. No. 70,355

Term of patent 14 years

(Cl. D52—2)

FIG. 1

FIG. 2

We claim:

The ornamental design for a dispenser for paper towels or the like, substantially as shown.
